FUR-UNHAIRING MACHINE

Julius Golding, Whippany, N. J., assignor to
Unity Machine Corporation, Newark, N. J., a
corporation of New Jersey

Application July 9, 1936, Serial No. 89,716

11 Claims. (Cl. 149—26)

My invention relates to improvements in fur-unhairing machines for removing the stiff or water hairs from the skins of fur bearing animals whereby the quality of the fur and its value from a commercial standpoint are increased.

Machines of the character referred to comprise, generally, an endless canvas apron mounted on rollers, one or more of which are driven to carry the pelts, pinned or otherwise secured to the canvas, over a stretcher-bar with an intermittent, relatively slow movement. As the pelts pass over the edge of this bar, the finer hairs are separated from the stiff or water hairs by a rotary brush, after which knives or shears come into play to cut off the stiff hairs. In practice there is generally a substantial space left between the adjacent pelts. In the various machines constructed heretofore, the canvas apron is always moved intermittently and at the relatively slow rate, whether or not a pelt at the time is passing over the edge of the stretcher-bar. These machines of the prior art, therefore, take an unnecessarily long time for the canvas apron to make one complete trip around its supporting rollers.

In the fur-unhairing machines used heretofore, all of the desired actions are not carried on entirely automatically, so that the attention of the operator to some of these is required.

With the foregoing in mind, it is one of the objects of my invention to provide an improved fur-unhairing machine of the character referred to in which, as each pelt passes beyond the stretcher-bar and a blank space begins to pass over the latter, movement of the canvas is automatically speeded up and changed from the intermittent, relatively slow movement to a movement at a relatively high and constant rate until the next pelt comes into position at the edge of the stretcher-bar.

Another object of my invention is to provide an improved fur-unhairing machine of the character referred to in which all of the desired operations are carried on automatically, so that none of these require the attention of the operator, the features of invention in the present application are in the form of improvements over my co-pending application, Serial No. 32,140, filed July 19, 1935.

Other objects and advantages will hereinafter appear.

For the purpose of illustrating my invention, an embodiment thereof is shown in the drawings, 55 wherein,

Figure 1 is a simplified elevational view, looking at one side of the machine;

Fig. 1a is a sectional view, the section being taken on the line 1a—1a in Fig. 1;

Fig. 2 is a simplified elevational view, looking 5 at the other side of the machine;

Fig. 2a is an elevational view of a beater for fluffing up the fur;

Fig. 3 is an end elevational view of the machine, looking toward the right in Fig. 1; 10

Fig. 3a is a fragmentary, plan view of the canvas apron and associated parts for holding the pelts;

Fig. 3b is an enlarged view, taken from Fig. 3a, showing the securing prongs for the pelts; 15

Fig. 3c is a section on the line 3c—3c in Fig. 3b;

Fig. 4 is a sectional view, the section being taken on the line 4—4 in Fig. 3;

Fig. 5 is an enlarged sectional view, the section being taken on the line 5—5 in Fig. 4;

Fig. 5a is a sectional view, the section being taken on the line 5a—5a in Fig. 4;

Fig. 6 is an enlarged fragmentary view taken from Fig. 1, and partly in section, the section 25 being taken on the line 6—6 in Fig. 3;

Fig. 7 is a plan view of Fig. 6;

Fig. 7a is an enlarged sectional view, the section being taken on the line 7a—7a in Fig. 7;

Fig. 8 is an enlarged sectional view, the section being taken on the line 8—8 in Fig. 3;

Fig. 9 is a sectional view, the section being taken on the line 9—9 in Fig. 8;

Fig. 10 is an enlarged sectional view, the section being taken on the line 10—10 in Fig. 3; and 35

Fig. 11 is a sectional view, the section being taken on the line 11—11 in Fig. 10.

With reference to the drawings, the reference numeral 10 designates the frame of the machine in which is journaled a drive shaft 11 which is 40 rotated continuously and at a constant rate by power supplied to the pulleys 12.

The frame supports rollers 13, 14 and 15, and a stretcher-bar 16 about which the canvas apron 17 passes.

The canvas apron 17 is provided with sets of barbs or pins 18 spaced with respect to each other and upon which the front edge portions of the pelts 19 are placed to hold them for movement along with the canvas apron. Canvas flaps 50 20 cover up these front edge portions of the pelts to assist in holding them in place to pass properly over the rollers and around the stretcher-bar. A roller 21 operates to guide both sides of the canvas apron at the stretcher-bar.

For the purpose of imparting intermittent movement to the canvas apron at the relatively slow rate, as the pelts pass around the stretcher-bar, a ratchet mechanism, designated generally by the reference numeral 22, is operated from the drive shaft 11 by a rod 23 journaled at its lower end to a crank pin 24. The ratchet mechanism includes a ratchet wheel 25 fixed on a shaft 26 to which is also fixed a gear 27 which meshes with another gear 28. The gear 28 is fixed with respect to the roller 13 and for rotation about the same axis of rotation as the latter. From the foregoing it will be seen that as the drive shaft rotates continuously and at a constant rate, the driving roller 13 is caused to rotate intermittently and at a relatively slow rate to impart the same movement to the canvas apron 17. A holding dog 29 is associated with the ratchet wheel 25, as shown in Fig. 1.

As the pelts pass around the edge of the stretcher-bar 16, a rotary brush 30 operates to brush down the hairs directly at the edge of this bar. The brush 30 is supported for rotation on a spindle 31 journaled in the ends of bars 32 and 33. The rear end of the bar 33 is pivotally connected by a pin 34 to a rocker arm 35 fixed on a shaft 36.

The brush 30 is driven from the drive shaft 11 through a sprocket gear 37 fixed on the latter, a sprocket chain 38, a sprocket gear 39 loose on the shaft 36, a gear 40 also loose on the shaft 36 and fixed for rotation with the sprocket gear 39, a gear 41 which meshes with the gear 40 and is rotatable on the pin 34 fixed in the bar 33, a sprocket gear 42 loose on the pin 34 and fixed for rotation with the gear 41, a sprocket chain 43, a sprocket 44 rotatable on a pin 45 carried by the bar 33, a gear 46 loose on the pin 45 and fixed for rotation with the sprocket gear 44, and a gear 47 which meshes with the gear 46 and is fixed on the spindle 31.

A spring 48 operates to exert a downward pull on the bar 33 to keep a roller 49 always in contact with a fixed cam surface 50, the roller being carried by the bar 33.

The bar 32 is provided with a similar roller 51, and is supported in the same manner and for the same movement as the bar 33.

Movement is imparted to the rocker arm 35 by a tension spring 52 and a rod 53 having a bifurcated end 54 which embraces the drive shaft 11. This end of the rod 53 carries a roller 55 which is always held, by the action of the tension spring 52, in engagement with the surface 56 of a cam 57 fixed on the drive shaft 11.

The means for cutting off the stiff or water hairs of the pelts comprises a knife blade 58 carried by arms 59 and 60 supported for rocking movement by a shaft 61, and a rotary blade 62 secured to the ends of arms 63 which are fixed on a shaft 64.

The blade 58 is caused to oscillate by an eccentric 65 which is loose on the drive shaft 11 and which is connected by a rod 66 to the supporting structure of the knife 58. The blade 62 is caused to rotate from the drive shaft 11 through a sprocket gear 67 fixed on the shaft 64, a sprocket chain 68, and a sprocket gear 69 which is loose on the drive shaft 11 and which is fixed to a collar 70 also loose on the shaft 11. This collar is fixed to the eccentric 65 as shown in Fig. 11, and is provided with an annular groove 71. A bolt 72 extends through the collar 70 and the eccentric 65, and the end thereof is held by a spring 73 in a socket 74 in a flange 75 keyed to

the drive shaft 11. It will be seen that in this position of the parts, rotation of the drive shaft 11 causes operation of the eccentric 65 and rotation of the sprocket gear 69, whereas upon withdrawal of the bolt 72 from the socket 74, the eccentric 65 and the sprocket gear 69 are disconnected from operation although the flange 75 continues to rotate since it is fixed on this shaft.

For the purpose of causing the canvas apron 17 to speed up automatically when the spaces between the pelts are passing around the stretcher-bar 16, brush rollers 76 and 77 are provided and are disposed as shown more clearly in Fig. 6.

The roller 76 is supported from arms 78 and 79 pivotally connected to straps 80 which are fixed to the frame of the machine. A shoe 81 engages the roller 76 and is supported by links 82 rigidly bolted at their upper ends to arms 83 fixed on a shaft 84. The shoe 81 is yieldingly held against the brush 76 by a tension spring 85 connected to an arm 86 which is fixed to the shaft 84. Also fixed to the shaft 84 is a switch member 87 provided at its lower end with an electrical contact 88 disposed to engage a fixed contact 89.

The brush roller 77 is supported from arms 90 at opposite ends thereof and which are fixed on a shaft 91 to which is also fixed a switch arm 92 provided at its lower end with an electrical contact 93 disposed for engagement with a fixed contact 94. The brush 77 is yieldingly held in contact with the canvas apron 17 by a tension spring 95 connected to an arm 96 fixed on the shaft 91.

The canvas apron 17 is driven at the constant, relatively high rate of speed from a shaft 97 through a sprocket gear 98 fixed on this shaft, a sprocket chain 99, a sprocket gear 100 mounted on the shaft 26 through a conventional free-running clutch or so-called free-wheeling device 101, the gear 27, and the gear 28. The drive roller 13 and the gear 28 are supported for rotation at the upper ends of levers 103 which are loose on the shaft 26. A tension spring 104 connected to the lower end of one of the levers 103 operates to urge the drive roller 13 away from the rollers 14 and 15 to keep the canvas apron 17 taut.

The shaft 97 is driven from the shaft 11 through a sprocket gear 105 fixed on the latter, a sprocket chain 106, and a sprocket gear 107 loosely mounted on the shaft 97 and fixed with respect to a friction clutch part 108 which is also loose on the shaft 97. Complementary to the clutch part 108 is another clutch part 109 splined to the shaft 97. Upon excitation of an electromagnet 110 of any suitable construction, a lever 111 is caused to pivot about its supporting pin 112 to cause movement of a collar 113 to the left, as viewed in Figs. 4 and 5, whereupon the clutch parts 108 and 109 are engaged to cause the shaft 97 to rotate, the collar 113 being splined on this shaft.

Mounted on the shaft 97 is a sprocket gear 114 and a free-running clutch or free-wheeling device 115, the arrangement being such that when the shaft 97 is rotated in a clockwise direction, as viewed in Fig. 1, the sprocket gear 114 is rotated with this shaft, but if the shaft 97 ceases to rotate, the sprocket gear 114 can continue to rotate in the clockwise direction, for the purpose which will hereinafter appear.

The sprocket gear 114 is connected by a sprocket chain 116 to a sprocket gear 117 fixed with respect to a flywheel 118 fixed on a shaft 119.

Associated with the fly-wheel 118 is a weight 120 pivotally mounted on a pin 121 fixed in the flywheel, and another weight 122 pivotally mounted on a pin 123 also fixed in the flywheel. The pin 121 has a sliding fit in an arcuate slot 124 with which the weight 122 is provided, and the pin 123 has a sliding fit in an arcuate slot 125 with which the weight 120 is provided.

In the drawings, the various parts carried by or associated with the fly wheel 118 are shown in the respective positions they assume when the shaft 119 is rotating. That is, with the weight 120 and 122 moved outwardly by the centrifugal force, both a link 126 connected to the weight 120 and a link 127 connected to the weight 122 are pulled radially outwardly away from the axis of rotation to tilt bell cranks 128 and 129 and move pins 130 and 131 to the right so that their ends project outwardly beyond the sprocket gear 117, as shown. In this position of these rods, a thrust bearing 132 on the shaft 109 presses against a pivotally mounted lever 133 to place the latter in the position shown.

The lever 133 is connected by a rod 134a to the arm 135 of a belt crank supported by a bolt 136 for pivotal movement. A lever 137, mounted for pivotal movement on a pin 138, rests on the end of the arm 139 of the bell crank, and is held in engagement therewith by a tension spring 140. The lever 137 is disposed as more clearly shown in Figs. 10 and 11, so that when it is raised, the end portion 141 thereof is moved into the path of a cam surface 142a with which the bolt 72 is provided, to withdraw the bolt from the socket 74, whereupon the eccentric 65 and the sprocket gear 69 are disconnected from rotation with the drive shaft 11 to stop movement of the knife blades 58 and 62.

The lever 133 is connected by a rod 142 to a bell crank 143 supported at 144 for pivotal movement to pull in on or let out a flexible connection 145.

The connection 145 is connected to the end of an arm 146 fixed on a shaft 147. Arms 148, fixed to the shaft 147 at opposite ends thereof, support a roller 149 provided with prongs 150. Also fixed on the shaft 147 is an arm 151 carrying at its free end a weight 152. As shown in Fig. 6, each of the prongs 150 is disposed at an angle to the radial line from the axis of rotation of the roller 149.

As shown in Fig. 1, the switches 88, 89 and 93, 94 are connected in parallel in the supply circuit for the electromagnet 110, so that when either one of these switches is closed the electromagnet is energized to apply the clutch 108, 109, the electromagnet being deenergized and this clutch released when both of these switches are open.

The operation of the machine will now be explained.

With the switches 88, 89 and 93, 94 closed, the clutch 108, 109 will be applied so that the shaft 97 is driven from the shaft 11, rotating in a clockwise direction, as viewed in Fig. 1. The drive roller 13 is now rotating continuously at the relatively high rate of speed on account of the connection to the shaft 97, provided by the sprocket chain 99. The sprocket gear 114 is also rotating with the shaft 97 in the clockwise direction as viewed in Fig. 1, to cause the flywheel 118 to also rotate in this direction, whereupon the pins 130 are held in the position shown to cause the lever 133 to pull to the right on the rod 142 and push to the left on the rod 134, as viewed in Fig. 4. On account of the connections as described

above, the lever 131 will be held in the raised position to keep the bolt 72 withdrawn from the socket 74, whereupon the eccentric 65 and the sprocket gear 69 are disconnected from rotation with the shaft 11. The knives 58 and 62 are therefore stationary, and the disposition of the lever 137 is such that the knives come to rest about at the respective positions shown in Fig. 1. Also, the rod 142, having been pulled to the right, as viewed in Fig. 4, the flexible connection 145 will have been taken in to raise the roller 149 against the action of the weight 152, so that the prongs 150 do not touch the canvas apron 17 as the part thereof between the belts 19 passes under the roller 149.

As the next belt 19 is drawn under the roller brush 16, the shoe 81 is raised to rotate the shaft 84 and open the switch 88, 89, on account of the construction and arrangement described. However, the energizing circuit for the electromagnet 110 remains complete because the switch 93, 94 is still closed. When the belt is drawn under the brush 17 the switch 93, 94 is also opened to deenergize the electromagnet 110 and release the clutch 108, 109. The shaft 97 then stops, but on account of the free-running clutch 115 the flywheel 118 can continue to rotate under the moment of inertia which has been stored in it. The knife blades 58 and 62, therefore, still remain stationary, until the flywheel finally slows down sufficiently to drop the lever 137 and thereby cause the eccentric 65 and the sprocket 69 to be driven from the shaft 11. The weight of the flywheel 118 and the arrangement and relation of the various parts are such that even after the clutch 108, 109 is released, and the canvas apron again is moved intermittently at the relatively low rate, the knives remain stationary until the brush 30 has an opportunity of making several strokes to sufficiently brush out the hairs of the belt at the edge of the stretcher-bar before the knives start cutting.

When the flywheel 118 stops rotating after release of the clutch 108, 109, the pins 130 and 131 are withdrawn to the left, as viewed in Figs. 8 and 9, to permit the bolt 72 to enter the socket 74 and also to permit the roller 149 to drop upon the belt under the action of the weight 152. The knives 58 and 62 are then set into motion, and the prongs 150 enter into the belt to act as a brake so that the belts cannot slide ahead under the brushing action of the brush 30. For this purpose, the bearings for the roller 149 are set snug, so there is a drag against rotation of this roller.

The canvas apron and the belts carried thereby are now being moved intermittently at the relatively low rate, under the action of the ratchet mechanism driven from the drive shaft through the connecting rod 23.

The arrangement and relation of the various parts and connections are such that during the periods of movement of the belts around the stretcher-bar, the brush 30 is in its forward position to brush down all the hairs, and the knives 58 and 62 are beginning to approach each other for the cut. Just as movement of the belt is about to cease, the brush 30 is withdrawn, and immediately thereafter the stiff water hairs spring out again, but the finer hairs do not. At about this instant, movement of the belt will have ceased, and the knives will engage to cut the stiff hairs which at this instant are the only ones which stick out in position to be cut. After this action, movement of the belt again starts

and the brush 30 is moved forward to brush down the next succeeding hairs which are now directly at the edge of the stretcher-bar 16.

This cycle of operation is repeated until the

- 5 pelt passes entirely around the edge of the stretcher-bar. As soon as the pelt has passed the roller 76 to permit the switch 88, 89 to close, the electromagnet 110 will again be energized to apply the clutch 108, 109, whereupon movement
- 10 of the knives 58 and 62 ceases and the canvas apron is again caused to move at the constant and relatively high rate of speed. As before, this action and the condition of the various parts continues until the next pelt moves into position
- 15 to raise both rollers 76 and 77 and open both switches 88, 89 and 93, 94 to again release the clutch 108, 109. The operation and action of the various parts is then repeated as explained above. On account of the angular disposition of
- 20 the prongs 150, they easily enter into and are easily withdrawn from the pelts as the latter pass along and cause the roller 149 to rotate in the clockwise direction as viewed in Fig. 6.

It is proposed to place a roller 153 ahead of the

- 25 roller 149 to roll the pelts flat against the canvas apron before they engage with the roller 149. The roller 153 is pressed downwardly against the canvas apron and the pelts by springs 154 disposed at the ends thereof.

- 30 The shape and disposition of the cam surface 50 is such that when the brush 30 is fully advanced, as shown in Fig. 6 by dash lines, it is directly at the edge of the stretcher-bar, and the shape of the cam 56 is such as to keep the brush 30 at this point as long as possible before the knives make the cut. In this way, the effect of the brush 30 to brush down the hairs is prolonged as much as possible and until the very instant that the knives 58 and 62 begin to come into play
- 35 40 to cut the stiff hairs which spring out instantly after the effect of the brush is removed. Therefore, all of the stiff hairs are cut off without cutting any of the desired, finer hairs.

A hand lever 155 is provided for pressing down

- 45 on the end 156 of the lever 137 to provide means for the operator to stop movement of the knives 58 and 62 if he might desire to do so at any time.

For the purpose of holding the pelts up after they have passed the roller 77, it is proposed to

- 50 stretch a canvas slip 157 between bars 158 and 159 so that the upper part 160 thereof is slightly below and parallel to the lower section of the canvas apron 17. The pelts, therefore, are supported by the part 160 until they pass over and
- 55 beyond the roller 15.

For the purpose of knocking off the pelts from the canvas apron after they have passed beyond the roller 15, a beater 161 is disposed at the position shown and is rotated from the shaft 36 through sprocket chains 162 and 163. As shown more clearly in Fig. 2a, the beater 161 comprises a plurality of relatively stiff leather or flexible metal straps 164 fixed to and extending radially outwardly from a supporting shaft 165. After the

- 60 65 pelts pass beyond the roller 15, they hang down from the flaps 20, and in continuing on are struck by the beater 161 and knocked off the canvas apron. The beater 161 also has the effect of fluffing up the fur.

- 70 75 The pressure exerted by the rollers 21 and the brush 76 on the pelts as they pass through smoothens or straightens them out on the canvas apron.

The brush 76 performs the functions of holding the hair under it during the cutting operation

and of operating the switch 88, 89 by raising or lowering the shoe 81, as explained.

From the foregoing it will be seen that I have provided an improved fur-unhairing machine in which all of the desired operating steps are accomplished entirely automatically, and in which provision is made for automatically speeding up the operation of the machine after each pelt has passed around the stretcher-bar and until the next pelt comes into position.

Although I have disclosed but one embodiment of my invention, it will be seen that various modifications and changes, such as in the size, shape and arrangement of the parts, might be made without departing from the spirit of my invention or the scope of the claims.

I claim as my invention:

1. In a fur-unhairing machine, cutting means, means for supporting a pelt and moving it with respect to the cutting means to cause the latter to cut hairs of the pelt, means for driving said cutting means, means for brushing down the hairs of the pelt and movable for such purpose into and out of a position to brush the hairs about to be cut, means for causing said cutting means and said brushing means to perform their respective functions alternately, means for imparting movement to said supporting means at a relatively slow rate during the hair-cutting operation, means for imparting movement to said supporting means at a relatively high rate, means for causing said seventh-named means to function only during the periods preceding and subsequent to the hair-cutting period, and means for disconnecting said cutting means from its driving means while the supporting means is moving rapidly and for a short period after the rapid movement ceases, only said brushing means functioning during said last period.

2. In a fur-unhairing machine, cutting means, means for supporting a pelt and moving it with respect to the cutting means to cause the latter to cut hairs of the pelt, means for driving said cutting means, and a roller provided with prongs and supported for movement to and out of a position whereat the roller presses against the pelt and the prongs pierce the pelt and withdraw therefrom as it moves on, and means supporting said roller for rotation and set to cause a drag against rotation of the roller.

3. In a fur-unhairing machine, cutting means, means for supporting a pelt and moving it with respect to the cutting means to cause the latter to cut hairs of the pelt, means for fluffing up the fur of the pelt after the hair-cutting operation comprising a rotatable shaft disposed below said supporting means and a plurality of relatively flexible beater elements each fixed at one end thereof to said shaft, and means for rotating said shaft whereby said elements become effective to beat against the pelt to fluff up the fur thereof and to knock off the pelt from said supporting means.

4. In a fur-unhairing machine, cutting means, means for supporting a pelt and moving it at a given rate with respect to the cutting means whereby the latter may cut the stiff or water hairs of the pelt, and means responsive to movement of said supporting means for increasing the rate of movement thereof subsequent to completion of the hair-cutting operation by the cutting means including a movable roller for engagement with a pelt on said supporting means, a shoe engaging the top of said roller and a switch associated with said member and responsive to movements of said

roller for making or disrupting a circuit which controls the rate of movement of the supporting means.

5. In a fur-unhairing machine, cutting means, means for supporting a pelt and moving it at a given rate with respect to the cutting means whereby the latter may cut the stiff or water hairs of the pelt, and means responsive to movement of said supporting means for increasing the rate of movement thereof subsequent to completion of the hair-cutting operation by the cutting means including a pair of movable members normally in engagement with the supporting means, each of the movable members controlling 10 an individual switch, said switches being connected in parallel in a circuit which controls the rate of movement of the supporting means.

6. In a fur-unhairing machine, cutting means, means for supporting a pelt and moving it with respect to the cutting means whereby the latter may cut the stiff or water hairs of the pelt, means for driving said cutting means, means for brushing down the smooth hairs of the pelt which are not to be cut, means for causing said cutting 20 means and said brushing means to perform their respective functions alternately, means for imparting movement to said supporting means at a relatively slow rate during the hair-cutting operation, means for imparting movement to said 25 supporting means at a relatively high rate during the periods preceding and subsequent to the hair-cutting operation, means for disconnecting said cutting means from the driving means for the latter periods, and inertia means effective to keep 30 the cutting means inoperative for a short period after said seventh-named means ceases to function whereby only said brushing means functions during said period.

7. In a fur-unhairing machine, cutting means, means for supporting a pelt and moving it with respect to the cutting means whereby the latter may cut the stiff or water hairs of the pelt, means for driving said cutting means, means for brushing down the smooth hairs of the pelt which 40 are not to be cut, means for causing said cutting means and said brushing means to perform their respective functions alternately, means for imparting movement to said supporting means at a relatively slow rate during the hair-cutting operation, means for imparting movement to said supporting means at a relatively high rate during the periods preceding and subsequent to the hair-cutting operation, means for disconnecting said cutting means from the driving means for the latter periods, and inertia means, acting in conjunction with an over-running clutch, effective to 45 keep the cutting means inoperative for a short period after said seventh-named means ceases to function whereby only said brushing means functions during said period.

8. In a fur-unhairing machine, cutting means, means for supporting a pelt and moving it at a given rate with respect to the cutting means whereby the latter may cut the stiff or water hairs of the pelt, means for driving said cutting means, means responsive to movement of said supporting means for increasing the rate of movement thereof subsequent to completion of the hair-cutting operation by the cutting means, clutch means for disconnecting the cutting means 10 from the driving means, and centrifugal control means responsive to said increased rate of movement of said supporting means for automatic control of the clutch means.

9. In a fur-unhairing machine, cutting means, means for supporting a pelt and moving it at a given rate with respect to the cutting means whereby the latter may cut the stiff or water hairs of the pelt, means for driving said cutting means, means responsive to movement of said supporting means for increasing the rate of movement thereof subsequent to completion of the hair-cutting operation by the cutting means, means responsive to said increased rate of movement of said supporting means for automatically disconnecting the cutting means from the driving means, and a pivoted lever for manually disconnecting the cutting means from the driving means at the will of the operator.

10. In a fur-unhairing machine, cutting means, means for supporting a pelt and moving it with respect to the cutting means whereby the latter may cut the stiff or water hairs of the pelt, means for brushing down the smooth hairs of the pelt, prior to the cutting operation on the stiff hairs, means for fluffing up the smooth hairs of the pelt after the cutting operation comprising a rotatable shaft disposed below said supporting means and a plurality of relatively flexible beater elements each fixed at one end thereof to said shaft, and means for rotating said shaft whereby said elements become effective to beat against the pelt to fluff up the fur.

11. In a fur-unhairing machine, cutting means, means for supporting a pelt and moving it with respect to the cutting means whereby the latter may cut the stiff or water hairs of the pelt, means for driving said cutting means, means for increasing the rate of movement of said supporting means subsequent to completion of the hair cutting operation by the cutting means, and a retarding means supported for movement to and out of a position whereat said means presses against the pelt to act as a retarding means and thus maintain the pelt in a taut condition, and mechanism operative to disconnect the cutting means from its drive and to move the retarding means out of position when said supporting means travels at the increased rate of movement.
